(57) CLAIM

The ornamental design for merchandising containers for vehicle lights, as shown and described.

DESCRIPTION

FIG. 1 is a front-side view of a merchandising container for vehicle lights showing the new design;

FIG. 2 is a rear-side view thereof;

FIG. 3 is a right-side view thereof;

FIG. 4 is a left-side view thereof;

FIG. 5 is a top-side view thereof;

FIG. 6 is a bottom-side view thereof; and,

FIG. 7 is a perspective view thereof.

The broken lines are for purpose of illustrating the environment of the article only and form no part of the claimed design.
